Primary Examiner — Cathron C Brooks*Assistant Examiner* — Sharon S Oum(74) Attorney, Agent, or Firm — Plumsea Law Group, LLCCLAIM

The ornamental design for a headset, as shown and described.

DESCRIPTION

FIG. 1 is a perspective view of a headset showing my new design;
FIG. 2 is a rear elevational view thereof;

FIG. 3 is a front elevational view thereof;

FIG. 4 is a side elevational view of one side thereof;

FIG. 5 is a side elevational view of the opposite side thereof;

FIG. 6 is a top plan view thereof; and,

FIG. 7 is a bottom plan view thereof.

The broken lines showing portions of the headset form no part of the claimed design.

1 Claim, 7 Drawing Sheets(56)
